(57) **CLAIM**

I claim the ornamental design for a punch, as shown and described.

DESCRIPTION

FIG. 1 is a perspective view of our new design for a punch;
FIG. 2 is front view thereof;
FIG. 3 is a left side view thereof;
FIG. 4 is a rear view thereof;
FIG. 5 is a right side view thereof;
FIG. 6 is a top view thereof;
FIG. 7 is a bottom view thereof;
FIG. 8 is a perspective view of a second embodiment of our new design for a punch;
FIG. 9 is front view thereof;
FIG. 10 is a left side view thereof;
FIG. 11 is a rear view thereof;
FIG. 12 is a right side view thereof;
FIG. 13 is a top view thereof; and,
FIG. 14 is a bottom view thereof.
The broken lines showing the bottom portion of the punch form no part of the claimed design.
